United States Patent Office

Des. 212,418
Patented Oct. 15, 1968

212,418

LAVATORY

Donald W. Doman, Janesville, Wis., assignor to Kohler
Co., Kohler, Wis., a corporation of Wisconsin

Filed Feb. 23, 1968, Ser. No. 10,702

Term of patent 14 years

(Cl. D23—58)

Fig. 1

Fig. 2

Fig. 3

Fig. 4

FIG. 1 is a perspective view of a lavatory, showing my new design;

FIG. 2 is a plan view of the lavatory shown in FIG. 1;

FIG. 3 is a sectional view of the lavatory taken on the plane 3—3 indicated in FIG. 2; and

FIG. 4 is a sectional view of the lavatory taken on the plane 4—4 indicated in FIG. 2.

The dominant features of the design reside in the portions shown in full lines.

I claim:

The ornamental design for a lavatory, substantially as shown and described.
